UNITED STATES PATENT OFFICE.

CHARLES CARLEY LEEDS, OF PITTSBURGH, PENNSYLVANIA.

ENLARGING ATTACHMENT FOR CAMERAS.

1,088,030.

Specification of Letters Patent.

Patented Feb. 24, 1914.

Application filed December 26, 1912. Serial No. 738,668.

To all whom it may concern:

Be it known that I, CHARLES CARLEY LEEDS, a resident of Pittsburgh, in the county of Allegheny and State of Pennsylvania, have invented a new and useful Improvement in Enlarging Attachments for Cameras, of which the following is a specification.

This invention relates to an enlarging attachment for cameras.

The object of the invention is to provide simple and improved means whereby enlargements may be made with an ordinary camera and lens, directly from photographic negatives or films, either in ordinary daylight or with artificial light, without the use of a specially arranged dark room.

A further object of the invention is to provide an enlarging attachment for cameras which is simple and inexpensive and may be readily folded or collapsed into compact form for storage or transportation.

The invention comprises the construction and arrangement of parts hereinafter described and claimed.

In the drawings Figure 1 represents a perspective view of an enlarging attachment embodying the invention, and showing same with a camera arranged in position on the frame; Fig. 2 is a longitudinal section, taken on the line 2—2, Fig. 1, the camera being omitted; Fig. 3 is a detail cross sectional view of the negative holder; and Fig. 4 is a detail cross sectional view showing a modification.

The enlarging attachment comprises a suitable frame or base, one portion of which is in the shape of a box or container 1, which may be made of any suitable size, proportions or material, and into which the parts of the enlarging attachment can be folded when the same is to be stored. Hinged to one edge of the open end of said box, as at 2, are a pair of bars or rods 3, rigidly connected at their outer ends by a strap or straps 4, preferably formed of thin sheet metal and nailed or tacked to the ends of the bars. Said straps form guides between which travels a frame or base member comprising side bars 5 and end bars 6 rigidly connecting the same. The width of this base or frame member is slightly less than the distance between the

bars 3, so that the outer frame member can be telescoped into the hinged frame member in collapsing or folding the enlarging attachment. Preferably, the inner end of either or both of the side bars 5 may be provided with a suitable stop 3^a to engage the straps 4 and limit the outward movement of the bars. Rigidly secured to the outer end 60 of the outer frame or base member are a pair of side standards or supports 7, slotted as at 8 to receive clamping bolts or screws 9 for adjustably securing thereto, at different heights, the side legs 10 of a table 11, upon 65 the upper flat surface of which is placed the camera 12.

The side bars 3 and 5, are provided with sockets or seats 12, in which may be removably secured, as by screws 13, the feet 14 of 70 uprights 15, having hooks 16 at their upper ends. Uprights 15 are hinged intermediate their ends, as at 17, and the upper members thereof are provided with edge lugs or projections 18, arranged, when the uprights are 75 opened, to engage the edges of the lower members, so as to maintain the upper and lower members in alignment with each other.

The rear or outer end of the box 1 of the frame is normally open, but is provided with 80 grooves or ways 19 along its edges to receive a sliding paper holding frame 20. The latter is indicated in cross section in Fig. 2 and its general features are the same as those of the ordinary printing out frame. That is to 85 say, it is provided with an inner flange 21 to receive the edges of a transparent sheet or wall 22, formed of glass or the like, and against which the sheet of sensitized paper which receives the light rays is placed and 90 held by the usual removable hinged back 23. The frame also is preferably slotted at one end, as at 24, and provided with side grooves or ways 25 to receive an opaque slide or wall 25^a, which also forms a focusing screen, as 95 will hereinafter appear. This opaque wall is on the other side of the transparent wall 22 from the sheet of sensitized paper and covers and protects the same from light rays except when removed. It is preferably 100 formed of some material of light color, such as stiff, white cardboard, paper, hard rubber or the like. Preferably, the edges of the slot or opening 24 are fitted with thin strips of

felt between which the slide 25^a is passed, so that the paper holding frame is light-tight, as will be readily understood.

Secured at its outer end to the inner wall 5 of the box 1, as by strips 26^b is a projecting member 27, having a projecting chamber 28 therein. Said member may be made of rigid material, such as wood, fiber, tin, or other metal, but preferably is made of some flexible material, such as cloth or other fabric or leather. The projecting member will be made of rigid material, when a considerable number of enlargements are to be made with the same camera and where the focal distance in the projecting chamber does not vary materially. It is made, however, of flexible material, such as fabric or leather, when different enlargements must be made under different conditions, requiring adjustment of or flexibility in the projecting member. The projecting member 27, in the form shown in the drawings, is made of some opaque fabric which is thoroughly light-tight, and which is provided on its outer surface with rings or loops 29, adapted to be caught over the hook 16 on uprights 15 to support said member. The projecting member is conical in shape, but may be made of the form of the ordinary leather bellows of a camera, and its reduced end is provided with a flexible band 30 formed, for example, of rubber, which is arranged to be sprung or stretched over the lens and shutter of the camera 12, as indicated in the drawings.

Camera 12 may be of any preferred type, but preferably is provided with the usual extensible bellows 31, forming a light-tight chamber therein, and with a longitudinally adjustable lens frame 32, the position of which may be adjusted for focusing by a screw 33, as is usual. At the rear of the camera is the usual spring-actuated ground glass frame 34, in front of which may be inserted a negative holder 35. This is of the usual type of ordinary glass plate holder, except that the partition separating the opposite sides thereof is cut out at the center, merely leaving edge strips 36, which form shoulders against which the glass negative is placed, and which in enlarging, form a mask for producing an even border for the picture. Said negative holder is provided with the usual slide or cover 37.

55 Preferably, the box 1 is provided with a suitable cover or door 38, hinged at one edge thereof, as at 39, and which is arranged to inclose all the parts of the apparatus when folded.

60 The apparatus is used in the following manner: The apparatus being opened out and the parts arranged as in Fig. 1, camera 12 is placed in position on the table 11 and this is adjusted to the proper level, accord-

ing to the size of the camera or whether the latter is placed on its side or end. The reduced elastic end 30 of the projecting member is then slipped over the shutter of the camera to prevent the admission of any light into the chamber 28 except that coming through the camera lens. The negative to be enlarged, in its holding frame 35, is then inserted into position in front of the ground glass 34 of the camera. The paper holding frame 20, previously loaded with sensitized paper and with the screen 25^a therein, is slid into position in the rear end of the box or frame 1. The projecting member 27 is preferably provided with a peep-hole or sighting aperture 40, through which the screen 25^a may be viewed from the outside thereof. This aperture is ordinarily closed by a flap or door 41 of any preferred type. The cover 41 of the peep-hole is lifted and the shutter of the camera is opened, when light will pass through the ground glass 34, which diffuses the same, then through the negative and through the lens of the camera and to the chamber 28 within the projecting member 27. By operating the adjusting screw 33, the lens frame 32, and the lens carried thereby, are then moved until the image on the negative is clearly focused upon the screen 25^a, as seen through the peep-hole 40. The shutter is then closed and the screen 25^a is withdrawn from the end of the paper holder. The shutter of the camera is then operated to give the desired exposure and to permit the image to be received by the sensitized paper. This may be accomplished by operating the shutter lever through the flexible material as shown at 27^a, Fig. 4 of the projecting member, but if the member 27 is of rigid material it may be provided at its smaller end with a short sleeve 44 of flexible material having an elastic band 30^b fitting over the shutter case 42 and through which sleeve the shutter lever 43 may be operated. Screen 25^a is now re-inserted into the paper-holder and this is carried to a dark room where the paper is developed and fixed in the usual manner.

When it is desired to store the attachment, the camera is removed and the rings 29 taken off from the hooks 16. The uprights 15 are next removed from the base members 3 and 5 and the flexible member 27 is collapsed into the box 1, and the uprights placed therein. The table 11 is next adjusted to its lowest position and the supporting member 5 is telescoped inwardly toward the box 1, and when in its innermost position the bars 3 are folded inwardly on the hinges 2 into the frame. The cover 38 can then be swung around to close the box and protect all the parts therein.

In case a glass negative of the enlargement is desired, an unexposed plate is sub-

stituted for the transparent wall 22 and the operation of enlarging is carried out as before described.

The enlarging attachment described is simple and inexpensive and permits of the production of enlargements without a specially prepared dark room. While the sensitized paper must be placed in the holding frame in a dark room and the developing and fixing also done there, the printing or enlarging may be done in an open room by means of either an artificial or natural light, or may be done out of doors, if desired.

What I claim is:

1. An enlarging attachment for cameras, comprising a frame, a light-tight projecting member supported thereby and having a chamber therein, and a sensitized paper-holder supported by said frame in position to close one end of said chamber with the paper forming an end wall therefor, the other end of said member being arranged to fit over and inclose the shutter of a camera, said projecting member being provided with a peep-hole, whereby the image may be focused upon a screen in said paper-holder.
2. An enlarging attachment for cameras, comprising a box or container, an extensible supporting member hinged thereto, a light-tight extensible projecting member secured to said box and having a chamber therein, means for supporting said projecting member and a sensitized paper-holder supported by said box in position to close one end of said chamber with the paper forming an end wall therefor, the other end of said extensible projecting member being arranged to fit over and inclose the shutter of a camera, said paper-holder being arranged to support an opaque screen, and said projecting member having a sighting opening whereby the projected image may be focused upon said screen.
3. An enlarging attachment for cameras, comprising a box-like frame, supporting members hingedly connected thereto, a light-tight projecting member having a chamber therein, means for supporting said projecting member and a sensitized paper-holder removably secured in the open end of said box-like frame in position to close one end of said chamber with the paper forming an end wall therefor, the other end of said member being arranged to fit over and inclose the shutter of a camera, said projecting member being formed of flexible material, whereby the camera shutter may be manipulated through the wall of said projecting member from the outside thereof.
4. An enlarging attachment for cameras, comprising a frame, a light-tight projecting member supported thereby and having a chamber therein, a sensitized paper-holder removably secured in said frame in position

to close one end of said chamber with the paper forming an end wall therefor, and a table or support carried by said frame and arranged to loosely support a camera, the other end of said projecting member being arranged to fit over and inclose the shutter of a camera, and means whereby the projected image may be seen and brought to focus before exposure of the sensitized paper.

5. An enlarging attachment for cameras, comprising a frame, a light-tight projecting member supported thereby and having a chamber therein, a sensitized paper-holder removably supported in said frame in position to close one end of said chamber with the paper forming an end wall therefor, a camera and a table or support vertically adjustable on said frame and arranged to loosely support said camera thereon, the other end of said projecting member being arranged to fit over and inclose the shutter of a camera, means for adjusting the lens of said camera to focus the same, and means whereby the projected image may be seen to bring the same into focus.

6. An enlarging attachment for cameras, comprising a frame, a light-tight projecting member supported thereby and having a chamber therein, a sensitized paper-holder removably supported by said frame in position to close one end of said chamber with the paper forming an end wall therefor, the other end of said member being arranged to fit over the shutter of a camera, said paper-holder comprising a frame, a transparent wall therein, removable means for clamping a sheet of paper against one side of said wall, and an opaque wall or screen on the other side of said transparent wall and removable from said frame.

7. An enlarging attachment for cameras, comprising a frame, a light-tight projecting member supported thereby and having a chamber therein, a sensitized paper-holder removably supported by said frame in position to close one end of said chamber with the paper forming an end wall therefor, the other end of said member being arranged to fit over the shutter of a camera, said paper-holder comprising a frame, a transparent wall therein, and removable means for clamping a sheet of paper against one side of said wall, said frame being slotted at one end and provided with ways to receive an opaque slide on the other side of said transparent wall, said slide being removable from said frame to expose said paper.

8. An enlarging attachment for cameras, comprising a frame, a light-tight projecting member supported thereby and having a chamber therein, a sensitized paper-holder removably supported by said frame in position

sition to close one end of said chamber with the paper forming an end wall therefor, the other end of said member being arranged to fit over the shutter of the camera,
5 said paper-holder comprising a frame, a transparent wall therein, removable means for clamping a sheet of paper against one side of said wall, an opaque wall or screen on the other side of said transparent wall
10 and removable from said frame, said pro-

jecting member being provided with an aperture through which the projected image on said opaque wall may be seen, and means for covering and uncovering said aperture.

In testimony whereof, I have hereunto set 15
my hand.

CHARLES CARLEY LEEDS.
